AUTOMOBILE

Albert E. Snow, Aurora, Ontario, Canada

Application August 28, 1953, Serial No. 26,618

Term of patent 7 years

(Cl. D14—3)

To all whom it may concern:

Be it known that I, Albert E. Snow, a citizen of Canada, residing at 47 Wells Street, Aurora, Ontario, Canada, have invented a new, original, and ornamental Design for Automobile, of which the following is a specification, reference being had to the accompanying drawing, forming part thereof.

Fig. 1 is a perspective view of an automobile embodying my new design;

Fig. 2 is a fragmentary side view; and

Fig. 3 is a front end view thereof.

The dominant feature of my design resides in

the full line portion of the drawing, and in particular in the headlight portion.

I claim:

The ornamental design for an automobile, as shown and described.
